(57) CLAIM

The ornamental design for a wardrobe, as shown and described.

DESCRIPTION

FIG. 1 is a front perspective view of a first embodiment of a wardrobe showing the new design.

FIG. 2 is a front elevation view thereof.

FIG. 3 is a rear elevation view thereof.

FIG. 4 is a top plan view thereof.

FIG. 5 is a bottom plan view thereof.

FIG. 6 is a left elevation view thereof.

FIG. 7 is a right elevation view thereof.

FIG. 8 is another front perspective view thereof with a door thereof moved to an open configuration.

FIG. 9 is a front perspective view of a second embodiment of a wardrobe showing the new design.

FIG. 10 is a front elevation view thereof.

FIG. 11 is a rear elevation view thereof.

FIG. 12 is a top plan view thereof.

FIG. 13 is a bottom plan view thereof.

FIG. 14 is a left elevation view thereof.

FIG. 15 is a right elevation view thereof; and,

FIG. 16 is another front perspective view thereof with a door thereof moved to an open configuration.

The dashed lines in the drawings illustrate portions of the wardrobe that form no part of the claimed design.
